US00D937833S

(12) **United States Design Patent** (10) Patent No.: **US D937,833 S**
(45) Date of Patent: **** Dec. 7, 2021**

(54) **CONTROLLER**

(71) Applicant: **Facebook Technologies, LLC**, Menlo Park, CA (US)

(72) Inventors: **Peter Wesley Bristol**, Seattle, WA (US); **Yi-yaun Chen**, Seattle, WA (US); **Mauricio Romano**, Redmond, WA (US); **Peter Allan Chase Newbury**, Burlington, WA (US)

(73) Assignee: **Facebook Technologies, LLC**, Menlo Park, CA (US)

(**) Term: **15 Years**

(21) Appl. No.: **29/723,794**

(22) Filed: **Feb. 10, 2020**

(51) LOC (13) Cl. **14-02**

(52) U.S. Cl.

USPC **D14/388**; D21/333

(58) **Field of Classification Search**

USPC ..... D10/104.1, 50, 65, 758; D14/138 R, D14/138 AA, 138 C, 138 G, 144, 156, D14/147-148, 247-248, 341-347, 496, D14/203.1, 203.3, 203.4, 203.7, 314-318, D14/371, 374, 126, 129, 130, 137, 218, D14/240, 336, 388-389, 420, 426, 430, D14/186, 147-48; D21/333, 13, 27, 324, D21/328, 329-331, 325; D18/4.4-4.6, D18/6-7; D19/59-60, 113; D24/186 CPC A63F 13/24; A63F 13/06; A63F 13/218; A63F 13/23; A63F 13/25; A63F 2300/1087; G06F 3/03547; G06F 3/0393; G06F 1/162; G06F 1/1662; G06F 1/1671; G06F 1/1688; G06F 3/0219; G06F 1/1616; G06F 1/1626; G06F 1/1643; G06F 3/02; G06F 3/041; G06F 3/0412; G06F 3/0416; G06F 3/0488; G06F 3/04883; G06F 3/04886; H04M 1/021; H04M 1/0279; H04M 1/0202

(57) **CLAIM**

The ornamental design for a controller, as shown and described.

DESCRIPTION

FIG. 1 is a front perspective view of a controller showing the claimed design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines shown in the figures illustrate portions of the controller that form no part of the claimed design.

1 Claim, 8 Drawing Sheets
